US0D1098554S

(12) **United States Design Patent** (10) **Patent No.:** **US D1,098,554 S**
(45) **Date of Patent:** **** Oct. 14, 2025**

(54) **DUAL LUMINAIRE CONNECTOR**

(71) Applicant: **P4 Infrastructure, Inc.**, Milwaukee, WI (US)

(72) Inventors: **Joseph A. Diekfuss**, Waukesha, WI (US); **Christopher M. Foley**, Milwaukee, WI (US)

(73) Assignee: **P4 Infrastructure, Inc.**, Milwaukee, WI (US)

(**) Term: **15 Years**

(21) Appl. No.: **29/915,071**

(22) Filed: **Oct. 25, 2023**

Related U.S. Application Data

(62) Division of application No. 29/778,013, filed on Apr. 9, 2021, now abandoned, which is a division of application No. 29/666,016, filed on Oct. 9, 2018, now Pat. No. Des. 919,169.

(57) **CLAIM**

The ornamental design for dual luminaire connector as shown and described.

DESCRIPTION

FIG. 1 is a perspective view of a dual luminaire connector; FIG. 2 is another perspective view thereof;

FIG. 3 is a top view thereof;

FIG. 4 is a bottom view thereof;

FIG. 5 is a front view thereof;

FIG. 6 is a rear view thereof;

FIG. 7 is a side view thereof; and,

FIG. 8 is another side view thereof depicting the side opposite the side shown in FIG. 7.

1 Claim, 6 Drawing Sheets
